(57) **CLAIM**

The ornamental design for a golf ball and carrier with golf cleaning towel, as shown and described.

DESCRIPTION

FIG. 1 is a top front perspective view of the golf ball and carrier with golf cleaning towel showing my new design; FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a partial exploded perspective thereof;

FIG. 8 is an exploded right side elevation view thereof;

FIG. 9 is an exploded rear elevation view thereof;

FIG. 10 is an exploded front elevation view thereof;

FIG. 11 is an exploded top plan view thereof;

FIG. 12 is an exploded bottom plan view thereof;

FIG. 13 is a side sectional view along line 13-13 of FIG. 3; and,

FIG. 14 is an exploded top plan view with the towel element laid flat.

The broken lines shown in the drawings illustrate portions of the golf ball and carrier with golf cleaning towel that form no part of the claimed design.

The dash-dot-dot-dash line illustrates a boundary that forms no part of the claimed design.
